UNITED STATES PATENT OFFICE.

RALPH J. WELLS, OF DAYTON, OHIO.

RAILWAY TIE.

Application filed February 9, 1925. Serial No. 7,909.

My invention relates to railway ties and more particularly to an improvement of the construction disclosed in my co-pending application Serial No. 693,000, filed February 5, 1924. Whereas the prior construction referred to contemplated the employment of a wooden sleeper block superposed upon a cushion of asphalt or other resilient material, the present invention differs therefrom 10 by the employment of a metallic plate having downturned flanges extending within the receptacle enclosing the resilient cushion material and is further provided with sealing strips pressed into tight sealing engagement by the reaction or displacement of the 15 cushion material.

In railway track construction employing ties of the present type, there have been encountered conditions of use, wherein the tie construction referred to employing the wooden sleeper block is objectionable because of the height of such tie. This is particularly the case in laying railway tracks over concrete bridges and also in replacing 25 street railway track constructions laid on a concrete sub-bed, wherein the difference in elevation between the surface of the concrete sub-bed or that of the bridge floor and the level of the completed track is insufficient to 30 accommodate the height of the sleeper block. However, to meet certain traffic conditions, a metal bed plate is to be preferred to the wooden sleeper block.

In the present invention there is contemplated a skeleton tie structure to be embedded in concrete consisting of a pair of parallel spaced angle bars, having adjacent to their opposite ends, recessed seats or shallow receptacles in which is contained a quantity 40 of resilient cushion material. The preferred material is a plastic or semi-fluid form of asphalt, a comparatively shallow stratum of which is placed in the bottom of the receptacle or recessed seat and on which 45 rests a rail supporting plate. In the present instance the plates are provided with dependent flanges which project within the recess seat or receptacle and serve to guide the plates in vertical movement against the yielding tension of the cushion. These rail supports or sleeper plates may be flanged on all of their margins, thereby forming an inverted pan like head, which is telescopically disposed within the recessed seat or receptacle of the skeleton tie. The flanged mar-

gins of the plate approach sufficiently close to the side walls of the receptacle to prevent the exudation of asphalt or other cushion material under pressure, yet such fit or relative bearing of the dependent flanges of the 60 top plate in relation to the side walls of the recessed seat or receptacle, are not such as to present difficulties of manufacture. For economy of manufacture, the rail supporting plate, in the present construction may be 65 merely a section of appropriate size of standard iron channel. When such structural iron channel section is used, sealing strips of asbestos or other suitable material may be inserted to prevent the exudation of the 70 asphalt or cushion material at the ends of such sections, where the plate is devoid of a depending flange.

The object of the invention is to simplify the structure as well as the means and mode 75 of operation and construction of such railway ties, whereby they will be not only cheapened in construction, but will be more efficient in use, of increased durability and wearing quality, of compact form, accommodating an increased quantity of cushion material and unlikely to get out of repair.

With the above primary and other incidental objects in view as will more fully appear in the specification, the invention consists of the features of construction, the parts and combinations thereof, and the mode of operation, or their equivalents as hereinafter described and set forth in the 85 claims.

In the accompanying drawings, wherein is shown the preferred, but obviously not necessarily the only form of embodiment of the invention, Fig. 1 is a perspective view of a tie embodying the present invention 95 from which one of the sleeper plates has been removed. Fig. 2 is a detail perspective view of one end of the tie structure separated into its component parts. Fig. 3 is a longitudinal sectional view and Fig. 4 100 is a transverse sectional view through one end of the tie structure. Fig. 5 is a transverse sectional view of a track installation employing the tie forming the subject matter hereof. Fig. 6 is a detail perspective 105 view of a sleeper plate flanged on all its margins. Fig. 7 is a sectional view illustrating the comparative saving of excavation and concrete under street paving by use of present tie.

Like parts are indicated by similar characters of reference throughout the several views.

While the tie construction herein disclosed may be employed for open track installation, or in the construction of cross country trackage, it will find its greatest field of usefulness in urban construction, wherein the ties are usually embedded in a concrete foundation or road-bed. The primary purpose of this tie as well as the previous construction referred to is to afford a requisite degree of resiliency, which will not only improve trackage conditions, but when embedded in concrete sub-structure will absorb shocks and vibrations, and so prevent breakage and disintegration of the concrete sub-bed. The tie in such installation becomes in effect a transverse reinforcement member for the concrete foundation or road-bed, and so long as the concrete road-bed remains intact, it functions as a single enlarged sleeper or support, which sustains traffic pressure throughout the entire width of the track, and throughout as great length thereof as is being utilized. It is thus possible to utilize the entire bearing surface of the concrete foundation of the road-bed. Such concrete road-bed, however, if subjected to ordinary traffic shocks and constant impact of car wheels is liable to more or less breakage and disintegration. The skeleton structure of the present tie, which in its ultimate form is substantially an integral steel frame, not only serves to reinforce and tie together the concrete road-bed, enabling it to resist breakage, but the sleeper plates resiliently supported at opposite ends of the tie structure and forming the rest or support for the track rails afford the necessary resiliency and serve to cushion shock and vibration, thereby protecting the concrete foundation or road-bed against breakage and disintegration. Inasmuch as the shock or blow of car wheels upon an unyielding track structure is as detrimental to the rolling stock as it is to the track itself, the cushioning effect of the sleeper plate at the opposite ends of the present tie is equally advantageous to the railway track equipment. The use of the flanged plate in lieu of the wooden sleeper block before employed affords a compact construction, affording within the height of a few inches, the necessary resiliency, capable of absorbing shock and vibration.

Referring to the drawings, 1-1 indicates two metallic angle bars arranged in parallel spaced relation with their horizontal flanges directed one toward the other. Located adjacent to the opposite ends of the spaced angle bars and interconnected thereby are two pan like receptacles or recessed seats. For economy of manufacture, these receptacles or seats have been shown as two plates

3, having upturned terminal flanges 4, extending transversely from the upstanding flange of one angle bar to that of the other. The parts of the tie structure are shown in Fig. 2 disconnected from each other, wherein the seat plate 3 is clearly shown as a channel shaped member arranged transversely in relation with the angle bars 1-1. When in assembled relation the standing flanges of the angle bars 1-1 project above the plate 3 on opposite sides thereof and extend from one terminal flange 4 to the other, thereby forming the opposite side walls of an enclosure or recessed seat, of which the plate flanges 4 form the transverse or terminal walls. This seat plate 3 is united to the angle bars 1 by any suitable means, such as welding, riveting, bolting or other method of joining. It is obvious that in lieu of the channel shaped seat plate 3, a pan like receptacle complete in itself having side walls as well as end walls, may be substituted. Contained in each of the recessed seats or receptacles of the tie structure is a stratum 5 of resilient material. While other materials may be employed the preferred cushion 5 consists of a quantity of asphalt in a plastic or semi-fluid state. This material may be sufficiently dense to afford a rubber-like characteristic. This body of cushion material, whether of asphalt or other resilient material must have sufficient resistance to withstand the pressure of the traffic without, however, being rigid.

One of the difficulties in early attempts to employ asphalt or like material for cushioning effects in railway ties was the tendency for the asphalt to ooze out of the tie receptacle when subjected to heavy pressure. This tendency was especially prevalent during warm weather. The preferred consistency of the asphalt is one which will not have this tendency to ooze or flow, but which will maintain a semi-solid characteristic having a degree of resiliency slightly greater than that of wood.

Superposed upon the stratum 5 of cushion material is a sleeper plate 6, having dependent flanges 7, which extend telescopically within the recessed seat of the tie structure. The dependent flanges 7 may be formed on all sides of the sleeper plate as shown in detail in Fig. 6. However, for economy of manufacture, the sleeper plate 6 may consist of a comparatively short section of structural channel beam of such size as to fit easily and loosely, but comparatively close to the walls of the recessed seat or receptacle. The dependent marginal flanges 7, whether on the opposite margins only of the plate 6, as shown in Fig. 2, or on all margins of the plate as in Fig. 6 have a guiding function within the recessed seat or receptacle and prevent the sleeper plate 6 from becoming tilted or inclined. Moreover, these

flanges extending in proximate relationship with the side walls of the receptacle prevent the escape of the cushion material 5, which is confined within the recess formed by the 5 dependent flanges 7. When a section of structural channel beam is used as shown in Fig. 2, sealing strips or bars 8 of asbestos or other suitable material metallic angle bars being found quite efficient, are inserted be- 10neath the plate 6 at opposite ends of the recessed seat or receptacle in lieu of the terminal dependent flanges which are absent from the channel beam section. These sealing strips 8 do not extend entirely to the bottom 15 of the receptacle and lie closely adjacent to the terminal walls of the receptacle or recessed seat immediately beneath the top plate 6. The compression of the cushion stratum by the weight and impact of traffic exerts 20 both outward and upward pressure on such sealing strips, tending to press them more closely against the terminal walls of the receptacle and against the underside of the top plate 6, thereby effectually sealing any crev- 25 ice against the escape of the cushion material. By the use of such bars, independent of the sleeper, on all four sides thereof, the sleeper may be merely a flat plate as appears in Fig. 3.

30 Clamp bolts 9 extend through the tie structure, including the sleeper plate 6 and carry rail engaging clamp jaws 10, which serve to secure the track rail in place.

Because of its compact form and capability of affording the necessary and requisite resiliency in small compass, the present tie construction possesses advantages for use in other installations than those before mentioned, i. e. upon bridge structures and for 40 track replacement purposes. In new urban installations where standard or usual type of street paving is employed, the present form of tie will result in a great saving of labor, particularly for excavation, and a cor-

45 responding saving in material especially concrete. The use of the present form of tie structure converts the street paving foundation into track foundation, enabling the same concrete sub-bed to serve both purposes. In

50 Fig. 7, there is shown more or less diagrammatically the present tie structure in comparison with the ordinary wooden tie installation and with a section of standard street paving to illustrate comparatively the 55 resultant saving in excavation and material.

The section A shows the usual street paving employing bricks or paving blocks of approximately four and a half inches, laid upon a sand stratum of one and one half 60 inches, superposed upon the sub-bed of concrete six inches thick. Assuming that the track rails are of the standard six inch rail section, laid upon standard six inch wooden ties, it is necessary to concrete or ballast beneath such ties as shown at B, to a depth of

approximately six inches, thereby necessitating the excavation of an additional six inches below the bottom of the paving sub-bed, and a filling of grouting or ballast for this additional six inches of excavation below 70 the wooden tie and below the bottom level of the street paving foundation. By using the present form of tie structure as shown at C, Fig. 7, the track rail being the standard six inch rail section, the present tie 75 structure is embedded in the foundation of the street paving, occupying approximately one and a half inches at the top surface of such concrete sub-bed. In order to afford a foundation of full six inches of concrete or 80 grouting, below the present form of tie structure, it is necessary to excavate only an inch and a half below that required for the sub-bed for the paving foundation. This makes a difference of four and one half 85 inches in excavation and in grouting or concrete foundation necessary below the tie as compared with the use of standard wooden ties shown at B. As shown at C at least four and a half inches of the sub-bed or founda- 90 tion for the paving lies beneath the present tie structure and is utilized as foundation for the track as well as for the paving. This saving of approximately four and a half inches per tie of excavation, and such 95 foundation of grouting beneath the tie will at present rates of installation costs result in a saving of twelve hundred to sixteen hundred dollars per mile of track. Furthermore, inasmuch as the tie structure is em- 100 bedded directly in the paving foundation, which is a continuous unitary body of concrete, rather than resting upon sub-founda- 105 tions of concrete extending below the paving bed and comprising independent founda- 110 tion for each tie, the efficiency and durability of this construction is materially in- creased.

From the above description it will be apparent that there is thus provided a device 110 of the character described possessing the particular features of advantage enumerated as desirable, but which obviously is susceptible of modification in its form, proportions, detail construction and arrangement 115 of parts without departing from the principle involved or sacrificing any of its ad- vantages.

While in order to comply with the statute the invention has been described in language 120 more or less specific as to structural features, it is to be understood that the invention is not limited to the specific details shown, but that the means and construction herein disclosed comprise the preferred form of several modes of putting the invention into effect and the invention is, therefore, claimed in any of its forms or modifications within the legitimate and valid scope of the ap- 125 pended claims.

Having thus described my invention, I claim:

1. In a railway tie, a tie body having a pocket therein, a body of resilient material within the pocket and a section of channel beam inserted within said pocket with its channeled side resting upon the body of yielding material, and means for securing a track rail to the exposed side of the channel beam section.
2. In a railway tie body, having a recessed seat therein, a body of resilient plastic material confined within the recess of said seat, a metallic sleeper plate resting upon the resilient body and forming a closure for the recess of said seat to confine the resilient material thereto, and guide means for said sleeper plate embedded in said body of plastic material to prevent the tilting of said plate within the recess.
3. In a railway tie, a tie body having a pocket therein, a body of resilient semi-fluid material within the pocket, and a metallic sleeper plate having downwardly flanged margins inserted within the pocket and embedded in the body of resilient material therein.
4. In a railway tie, a tie body having a pocket therein, a body of resilient semi-fluid material confined within the pocket, and a concave sleeper member telescopically fitted within the pocket and forming a closure therefor to prevent the escape of said resilient material with its concave side resting upon the body of resilient material.
5. In a railway tie, a tie body having a pocket therein, a body of resilient material within the pocket, a metallic sleeper plate resting upon the body of resilient material and conforming to the pocket for which it forms a closure to prevent the escape of resilient material and dependent guide means upon the sleeper plate engaging within the pocket to prevent the displacement of the plate or resilient body.
6. In a railway tie, a tie body having a pocket therein, a body of resilient material within the pocket, a sleeper member inserted within the pocket and resting upon the body of resilient material, a sealing strip located wholly below the sleeper member and pressed into the angle formed by the

under side of the sleeper member and the wall of the pocket by the lateral and upward pressure of the resilient body under influence of pressure upon said sleeper member.

7. In a railway tie, a tie body having a pocket therein, a body of resilient material within the pocket, a sleeper member inserted within the pocket and resting upon the resilient body, and sealing strips of less depth than the pocket, simultaneously abutting the under side of the sleeper member and side wall of the pocket to prevent the escape of the resilient material under influence of lateral and upward pressure induced by the descent of the sleeper member.

8. In a railway tie, a tie body, a receptacle therein, a body of cushion material within the receptacle, a sleeper plate resting upon the cushion material and independent sealing members having substantially right angle seating surfaces engaging in the angles formed by the underside of the sleeper plate and the interior sides of the receptacle and pressed to position by the displacement stress of the cushion material to prevent the escape thereof.

9. In a railway tie, a tie body having a pocket therein, a body of resilient material within the pocket and a metallic closure plate for the pocket resting upon the body of resilient material for vibratory movement against the yielding resistance thereof and independent closure bars simultaneously bearing against the under side of the said plate and the interior walls of the pocket, closing such pocket against the escape of the resilient material.

10. In a railway tie, a tie body, a receptacle therein, a body of cushion material within the receptacle, a sleeper plate resting upon the cushion material, and sealing bars independent of the plate embedded in the top margins of the body of the cushion material and bearing against the under side of the sleeper plate and the interior walls of the receptacle to prevent displacement of the cushion material.

In testimony whereof, I have hereunto set my hand this 2nd day of February, A. D. 1925.

RALPH J. WELLS.
